UNITED STATES PATENT OFFICE.

ELMIRA PACE, OF LOUISVILLE, KENTUCKY.

TOILET ARTICLE.

1,362,892.

Specification of Letters Patent. Patented Dec. 21, 1920.

Application filed August 17, 1920. Serial No. 404,060.

To all whom it may concern:

Be it known that I, ELMIRA PACE, a citizen of the United States, residing at Louisville, in the county of Jefferson and State of Kentucky, has invented certain new and useful Improvements in Toilet Articles, of which the following is a specification.

This invention relates to toilet articles and has special reference to electrically heated 10 toilet articles such as combs, curling tongs and the like.

One important object of the invention is the production of an improved general construction for devices of this character.

15 A second important object of the invention is to provide an improved arrangement of heating element in such devices.

A third important object of the invention is to provide an improved form of heating 20 element particularly adapted for use with an improved form of toothed articles such as combs.

With the above and other objects in view, as will be hereinafter apparent, the invention 25 consists in general of certain novel details of construction and combinations of parts hereinafter fully described, illustrated in the accompanying drawings and specifically claimed.

30 In the accompanying drawings like characters of reference indicate like parts in the several views, and:—

Figure 1 is a side elevation, partly in section, of a curling tongs, constructed in accordance with this invention.

Fig. 2 is a plan view thereof.

Fig. 3 is a side elevation, partly in section, showing the invention as applied to a comb.

Fig. 4 is an enlarged detail section on the 40 line 4—4 of Fig. 3.

In the embodiments of the invention herein illustrated, and which are to be taken as typical of a variety of analogous devices, a suitable hollow handle 10 of wood, fiber, celluloid or other preferred material is provided. From this handle projects a tubular shank 11 and within the handle at the end opposite the shank is located one part of a connector 12 which can be joined by the 45 other part of such a connector (not shown) to a suitable source of electric current. From this connector extends a wire loop formed of resistance wire and constituting the heating element, one part of the wire being helically coiled as at 13 while the wire is

brought straight back from the remote end of the helix to the connector as at 14.

In the form of the device shown in Figs. 1 and 2 the outer end of the shank is expanded to form a head 15 and pivotally connected to the shank is a bent lever 16 carrying at its outer end a head 17, the two heads having their confronting faces flat so that they may properly press a lock or ringlet of hair. In order normally to hold the heads 65 together a spring 18 is employed while a thumb piece 19 serves to receive pressure from the thumb whenever it is desired to separate these heads.

In the form of the device shown in Figs. 70 3 and 4 a series of teeth 20 project from the shank and each tooth is hollow as shown at 21, the hollow of each tooth communicating with the hollow of the shank so that the helix coil which lies opposite each respective 75 tooth may be extended down into the tooth as at 22.

With such a construction as this it is apparent that any suitable metal may be utilized in forming the devices and, while it is 80 preferred to use aluminum, either plated or plain, iron, copper or any other metal may be used and the same may be left plain, polished, plated or ornamented as may be found desirable.

It will be particularly noted that the series 85 connected loops extending into the hollow comb teeth heat the teeth in a highly advantageous manner since the heat is practically uniform throughout the length of the tooth and consequently produces a better effect, 90 as for instance in combing damp hair to dry it the points of the teeth do not get chilled as is the case where solid teeth are employed.

There has thus been provided a simple 95 and efficient device of the kind described and for the purpose specified.

It is obvious that minor changes may be made in the form and construction of the invention without departing from the material principles thereof. It is not therefore desired to confine the invention to the exact form herein shown and described but it is wished to include all such as come within the 100 scope claimed.

Having thus described the invention, what is claimed as new, is:—

1. In an electrically heated toilet article, 105 a hollow shank, a series of hollow comb 110

teeth extending from the shank and communicating therewith, a heating helix extending longitudinally of the shank and having certain of its convolutions formed 5 into loops extending into the teeth.

2. In an electrically heated toilet article, a hollow shank, a series of hollow comb teeth extending from the shank and communicating therewith, a heating helix extending longitudinally of the shank and consisting of a 10 plurality of series of convolutions having a

common axis, said convolutions being of circular shape and uniform size, the adjacent series of convolutions being connected together by single convolutions each having 15 one side extended into a respective tooth substantially in an elongated V-shaped loop with the plane passing through the sides of the V at right angles to the axis of the heating helix.

20 In testimony whereof I affix my signature.
ELMIRA PACE.
